UNITED STATES PATENT OFFICE

110,510

DESIGN FOR A WINDOW GRILLE OR SIMILAR ARTICLE

John F. Winn, Jr., Norfolk, Va., assignor to The
J. G. Wilson Corporation, New York, N. Y., a
corporation of Virginia

Application July 10, 1936, Serial No. 63,757

Term of patent 14 years

To all whom it may concern:

Be it known that I, John F. Winn, Jr., a citizen of the United States, residing at Norfolk, county of Norfolk, and State of Virginia, have invented a new, original, and ornamental Design for a Window Grille or Similar Article, of which the following is a specification, reference being had to the accompanying drawing which forms a part thereof.

Fig. 1 is a front elevational view of a window grille or similar article embodying my new design; and

Fig. 2 is a vertical edge view thereof.

The grille of the present design is characterized by a series of links mounted in staggered rela-

tion upon a succession of transverse parallel rods forming substantially diamond-shaped areas with the rods passing through the minor axes thereof, each link having a pair of legs that diverge from an integral U-shaped connecting loop which forms with the rod a small substantially horseshoe shaped opening at each angle of the diamond-shaped areas excepting those coinciding with the side and bottom edges of the grille.

I claim:

The ornamental design for a window grille or similar article, substantially as shown and described.

JOHN F. WINN, JR.
